Primary Examiner—Antoine D. Davis*Assistant Examiner*—Patricia Palasik(74) *Attorney, Agent, or Firm*—Mehul R. Jani; Adan Ayala; Charles Yocum(57) **CLAIM**

The ornamental design for a handle for a saw, as shown and described.

DESCRIPTION

FIG. 1 is a perspective view of a handle for a saw showing the new design.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof; and,

FIG. 8 is a front perspective view in an open position thereof.

In the above drawings the broken lines and the areas within the broken lines form no part of the claimed design.
